BEAR FIGURE DEVICE FOR HOLDING TOYS,
CLOTHING OR THE LIKE

James F. Eden, 312 Three Oaks Road,
Cary, Ill. 60013

Filed Nov. 16, 1970, Ser. No. 26,022

Term of patent 14 years

Int. Cl. D21—01

U.S. Cl. D34—15

FIG. 1 is a front view of the bear figure device for holding toys, clothing or the like, embodying my new design;

FIG. 2 is a rear view thereof; and

FIG. 3 is a side view thereof.

The top of the basket shown in FIGS. 1 and 3 is planar and unornamental.

I claim:

The ornamental design for a bear figure device for holding toys, clothing or the like, as shown and described.
